UNITED STATES PATENT OFFICE.

STEPHEN MOLTRUP AND WILLIAM L. HORNER, OF BEAVER FALLS,
PENNSYLVANIA.

PRINTER'S CHASE.

No. 821,726.

Specification of Letters Patent.

Patented May 29, 1906.

Application filed May 26, 1905. Serial No. 262,491.

To all whom it may concern:

Be it known that we, STEPHEN MOLTRUP and WILLIAM L. HORNER, of Beaver Falls, Beaver county, Pennsylvania, have invented 5 a new and useful Printer's Chase, of which the following is a full, clear, and exact description, reference being had to the accompanying drawings, forming part of this specification, in which—

10 Figure 1 is a top plan view of a printer's chase constructed in accordance with our invention. Fig. 2 is a side elevation of the same. Fig. 3 is an enlarged plan view, partly broken away, of a corner portion. Fig. 4 is 15 a cross-section of Fig. 3, and Fig. 5 is a partial side elevation of the corner portion.

Our invention relates to the class of printers' chases, and is designed to provide a simple and efficient construction which will hold 20 the type firmly in position and support it rigidly on all sides.

Heretofore in printers' chases where slotted interfitting bars have been used these bars have been forced into clamping 25 position by means engaging their end portions. Such construction is ineffective, since owing to the elasticity of the metal the intermediate portion of the bar will bend and prevent proper holding of the type.

30 Our invention overcomes this difficulty; and it consists in providing a printer's chase with longitudinal and transverse sliding interfitting bars and employing quoins which back up those portions of the bars engaging 35 the type. In this manner the binding pressure is applied directly in line with the type and there is no liability to bending or bowing of the interfitting bars.

The invention also relates to an improved 40 corner-portion construction of the chase, to guides for the clamping-bars, and other constructions hereinafter more fully described and claimed.

In the drawings we show a frame having 45 longitudinal members with upper and lower plates 2 2' and end transverse members with similar plates 3 3'. The upper and lower plates 2 2' and 3 3' are separated by the central spacers 4 and the spacing corner-blocks 50.

5. These blocks are pinned through the members or strips of the side frame, and the corner-blocks are preferably square and provided with transverse grooves 6 and right-angled ribs 6' on both upper and lower faces.

The inner faces of the upper and lower frame 55 members are grooved or recessed at the corners in alinement with the ribs and grooves of the block, and separate bars or strips 7 are forced into the grooves, which extend partly within the frame members and partly within 60 the spacing-blocks. The ribs of the block are cut through by the right-angled recesses of the block, as shown in Fig. 3. The parts are then pinned together by small rivets or pins, as shown in Figs. 1 and 3, some of which 65 preferably extend through the strips 7. A strong rigid construction is thus afforded, the bursting strain at the corners being resisted by the ribs and holding pins or strips. The inner faces of the pairs of members of each 70 side are recessed to form guideways for the guide-head 8 for each slotted clamp-bar. These heads 8 are preferably T shape in cross-section and are of considerable length, so that they will not be liable to bind as they 75 are slid back and forth to bring them to the desired point. We have shown these heads as slotted at their inner ends to receive the several strips or bars 9, which make up the transverse clamping-bars A A and the longitudinal clamping-bars B B. The members 80 of the transverse bars and the longitudinal bars interfit with each other at their intersections, as shown in Fig. 4.

To hold the clamping-bars in adjusted position and force them against the type, we provide quoins which bear upon the central portions of the clamping-bars. We have shown the longitudinal bars B as held by quoins 10, which are shown as adjusted by 90 the intermediate screw and nut device 11. We have shown the transverse bars as provided with furniture or blocks 12 between the bars and the quoins 13. The quoins may be of any desirable construction and 95 may be tightened by wedges, screws, or any other suitable devices. The outer bearing-blocks 14 of the quoins are arranged to fit against the upper and lower members of each side frame, preferably by being notched 100 along their edges. The guide-heads 8 for the clamping-bars are also cut back slightly from the inner edges, so as to allow them to slide past the quoins.

The advantages of our invention result 105 from combining the interfitting clamping-bars with quoins which bear upon the intermediate clamping portions of these bars.

We thereby obtain an efficient and secure clamping of the type in the space between the four bars or a portion of such space. The clamping pressure being applied opposite to the type there is no danger of bending or bowing the clamping-bars. The structure is simple, may be cheaply made, and is found in practice to be highly efficient. The corner construction is simple and strong.

10 Many variations may be made in the form and arrangement of the frame, the interlaced clamping-bars, the quoins, &c., without departing from our invention.

We claim—

- 15 1. A printer's chase having a frame made up of separated members, with guideways between them, interfitting slotted longitudinal and transverse clamping-bars, and guideheads adapted to slide in said ways, said heads having elongated sliding portions and shank portions slotted to receive the end portions of said bars, together with quoins arranged to hold the bars in clamping positions; substantially as described.
- 20 2. A printer's chase having a frame with upper and lower bars, said bars abutting against each other at the corner and having a spacing-block with strips forced into mating recesses in the corner-block and ends of the corner members; substantially as described.
- 25 3. A printer's chase having a frame with upper and lower bars, said bars abutting

against each other at the corner and having a spacing-block with strips forced into mating recesses in the corner-block and ends of the four corner members, and transverse rivets or pins extending through the spacing-block and four members; substantially as described.

4. A printer's chase having a frame with upper and lower plates beveled at the corners of the frame, a spacing-block between the plates at the corner, said block having ribs fitting within recesses in the plates and removable strips or bars fitting in grooves in the spacing-block and frame members; substantially as described.

5. A printer's chase having a frame with upper and lower plates or bars beveled and fitting together at the corner, a spacing-block between the four plates at the corner, said block having ribs fitting within grooves in the upper and lower plates, the block and plates having cross-grooves, removable bars fitting in said grooves, and pins arranged to hold the bars and block together; substantially as described.

In testimony whereof we have hereunto set our hands.

STEPHEN MOLTRUP.
WILLIAM L. HORNER.
